UNITED STATES PATENT OFFICE

FRANK B. WHITE, OF LA JOLLA, CALIFORNIA, ASSIGNOR TO ROBURKE, WHITE MANUFACTURING COMPANY, OF SAN DIEGO, CALIFORNIA, A PARTNERSHIP COMPOSED OF REEVES L. ROWE, OF SAN DIEGO, CALIFORNIA, AND FRANK B. WHITE AND J. McDONALD BURKE, BOTH OF LA JOLLA, CALIFORNIA

BRAKE LEVER CONSTRUCTION

Application filed September 17, 1928. Serial No. 306,522.

This invention relates to a lever construction, being particularly useful in levers used on motor vehicles for setting the emergency brake, though not in any sense limited to the one use named. It is a primary object and purpose of the invention to make a lever of this kind and equip it with means whereby it may be moved in one direction freely but is automatically stopped from movement in the opposite direction, this being accomplished without the use of the usual ratchet and pawl devices almost universally used at present. A further object of the invention is to provide the lever with automatically operating securing means for holding the lever in any position to which it may be moved, the positions which the lever may occupy being indefinite in number and not restricted to a certain definite number dependent upon the number of ratchet teeth which a ratchet may have with the impossibility of the lever occupying positions between those prescribed by consecutive teeth of the ratchet. A still further object of the invention is to construct a lever of this character which is noiseless in operation, and to equip it with means for releasing the lever for movement in the direction that it is normally stopped from movement, said releasing means being as freely and easily operated when the lever is drawn to the extreme of its movement and has heavy strain thereon as it is when the strain is little or nothing.

For an understanding of the invention by means of which these ends, together with many others not enumerated at this point, are attained, reference may be had to the following description, taken in connection with the accompanying drawings, in which, Fig. 1 is a side elevation with parts broken away and shown in section, illustrating one form of construction of the lever.

Fig. 2 is a fragmentary side elevation, enlarged, of the gripping portion of the lever, parts being broken away to better show the construction and operation thereof.

Fig. 3 is a fragmentary vertical transverse section thru the lever and associated parts, the section being taken in front of the gripping roller and looking back toward the same.

Fig. 4 is a fragmentary side elevation and partial section of a modified form of construction embodying the invention.

Fig. 5 is a vertical transverse section substantially on the plane of line 5—5, of Fig. 4.

Fig. 6 is a view similar to Fig. 4, of a still further modified form of construction embodying the invention, and

Fig. 7 is a section similar to Fig. 5, taken on the plane of line 7—7, of Fig. 6.

Like reference characters refer to like parts in the different figures of the drawings.

In the construction shown in Fig. 1, a transmission case 1 has an arc shaped sector 2 of metal secured thereto by bolts or set screws 3, a link 4 being attached to the other end of the sector at one end and having connection to the transmission case at its lower end serving to hold the sector in rigid relation to its support, the transmission case. A lever 5 is pivotally mounted between its ends on a stud 6 projecting from the cover of the transmission case 1, the lever at its lower end having a rod 7 connected thereto which leads to the rear and is operatively connected with the brake bands of the motor vehicle with which the transmission and lever is used. This is a common and well known method of mounting emergency brake levers, and the brakes are tightened and held against the brake drums by drawing the upper end of the lever to the rear, the usual lever having a pawl thereon to engage with a ratchet cut in the lower side of the sector to hold the lever from return forward movement.

The sector 2, in the present construction is wider than the usual sector used and its under surface is plain and curved around stud 6 on a radius extending from the center of stud 6 to the sector. A block 8 is located against the lever 5 below the sector and is permanently secured to the lever by screw 9 and rivet 10. It is evident that this block may be cast integral with the lever quite as well as in effect it is integral therewith through the permanent connection made. A plate 11 of relatively thin metal is placed alongside of the side of the block farthest from the lever and is secured thereto, screw 9 passing through the plate. The upper side

of the block is cut with a downward and forward incline, as indicated at 12, and at its front upper portion is provided with an upwardly extending abutment 13, having a recess in its rear side to make a seat for one end of a coiled spring 15, the opposite end of which bears against a roller 16 located between the inclined upper side 12 of the block and the curved under side of section 2. The 10 spring under compression has a normal tendency to force roller 16 up the incline 12 and tends to wedge the roller between said incline and the under side of the sector. Plate 11 serves as a means to prevent endwise movement of the roller and loss thereof, movement in the opposite direction being stopped by the lever as shown.

A bell crank lever having a horizontal arm 17 and a vertical arm 18 is pivotally mounted at 19 on the block 8. The arm 18 at its upper end is bent to extend over the block, lying between the same and the under side of the sector, and back of the roller 16 as indicated at 20. The arm 17 at its free end is 25 turned outwardly to make an ear 21 to which the lower end of an operating rod 22 is connected. Rod 22 extends upwardly alongside of the upper portion of lever 5 and at its upper end passes through a laterally projecting portion 5a thereof, being equipped at its upper end with a button 23 which partially enters a recess made in the upper end of the lever. A coiled compression spring 24 is seated in the recess between the bottom thereof and the lower end of the button 23 and exerts force to elevate the rod 22 and move part 20 30 of arm 18 away from the roller 16.

On rearward movement of the upper end of lever 5, roller 16 has a tendency to ride 40 down the incline 12 and the lever is freely movable to the rear. The movement is unaccompanied by noise of any description, as contrasted to the passage of the usual pawl over the teeth of a ratchet. The spring 15 keeps the roller in upper position, however, and immediately that the lever is released and tends to return in a forward direction, due to the pull exerted on the lower end thereof by rod 7 connected with the brakes, roller 16 45 wedges between the block 8 and sector 2 and positively stops return movement. If it is desired to release the lever, button 23 is depressed, thereby moving part 20 against the roller to move the roller forward and release 50 the lever from the sector, whereupon the lever may be moved in a forward direction as long as the button is held depressed.

The construction described is simple but 55 particularly effective in use. The lever may be drawn back to the desired position for setting the brakes and will remain in such position. There is no necessity for either stopping at one notch in the sector where the brakes are not tight enough to be effective, or for exerting very heavy force on the lever

to draw it back to the next notch in order to render the brakes effective, this construction not being limited in any way as to effective positions it shall occupy. The release is easy and does not require exceptional 70 strength on the part of the operator as when the brakes are set with the ratchet and pawl construction ordinarily used. Absolute security against connection is had. The roller is hardened to be able to withstand all strains 75 brought against it and the sector is widened to afford the necessary bearing surface therefor.

In Figs. 4 and 5 a modification in structure is shown, the sector being slotted lengthwise 80 to make two spaced apart portions 2a and the lever enlarged and provided with an opening therethrough through which the sector passes. This enlargement is indicated at 25 and the opening therethrough has an underside 12a inclined upwardly and to the rear on which the roller 16 is placed, spring 15 acting on the roller bearing at its outer end against a plate 26 fastened to the front side of the lever. A finger 27 having an inclined lower end 27a is secured to the lower end of the push rod 22 and is guided between the rear side of the enlargement 25 of the lever and a second plate 28 fastened to the rear side of the enlargement as shown. The 90 lower inclined end of finger 27 comes back of the roller 16 and on downward movement of the push rod, the finger acts to force the roller forward against the spring and disengage it from its wedged position. The 95 slot between the two parts 2a of the sector permits the free passage of the finger in the movement of the lever from front to rear and return.

In Figs. 6 and 7, a still further modification 105 is shown, and one which for some reasons is preferred. The lever 5 is enlarged as before though differently formed as indicated at 29 and the sector 2, not slotted, passes therethrough. The upper side of the opening is 110 formed with a downward and rearward incline and the roller 16 is mounted on the upper side of the sector and spring 15 disposed between the roller and plate 26a attached to the lever above the sector. The wedging 115 action due to the spring and the incline 12b is identical with that in the previously described constructions. On the lower end of push rod 22 a U-shaped stirrup 30 is secured 120 having depending legs 31, the lower ends of which are cut on an incline, as indicated at 31a, and coming directly back of the roller, being held against the enlarged portion 29 of the lever by plate 32 as shown. This construction works for the disengagement of the roller from wedging position the same as that shown in Figs. 4 and 5, but is more satisfactory in that a wider bearing on the roller may be had, furthermore the sector need not be slotted.

The constructions described are practical and efficient and work to positively hold the lever in any position to which it may be moved in one direction. The release for movement in the opposite direction is sure and may be easily operated. Various other modified forms of construction for embodying the invention may be constructed, and I, accordingly, do not consider my invention as limited to specific constructions shown, but desire that the invention be considered to comprehend any and all forms of structure which come within the scope of the appended claims defining the invention.

15 I claim:

1. In a brake lever construction, a pivoted lever having an opening spaced from the pivot and extending in a plane at right angles to the axis of the pivot, a quadrant concentric with said pivot and extending through said opening in the lever and having one of its curved sides bearing against a side of said opening, a roller located in said opening and interposed between the opposite curved side of said quadrant and the opposite side of said opening, said opposite side of said opening being inclined relative to the curved surface of the quadrant, a plate closing each side of said opening, a spring 30 interposed between said roller and one of said plates, said spring tending to thrust the roller into pinching engagement between the quadrant and the respective side of said opening, a wedge extending into said opening and engaging one of said plates, and means mounted on the lever for moving said wedge longitudinally to engage said roller and move it against action of said spring.

2. In a brake lever construction, a pivoted lever having an opening spaced from the pivot and extending in a plane at right angles to the axis of the pivot, a quadrant concentric with said pivot and extending through said opening in the lever and having its outer or far side, with reference to the axis of the lever, bearing against a side of said opening, said quadrant consisting of two concentric members spaced axially to form a long slot therebetween, said opening in the lever being enlarged at its inner side and having an inclined wall juxtaposed to the curved face of the quadrant, a roller between the quadrant face and the inclined wall, spring means to normally wedge the roller therebetween, a plate fixed alongside of the lever and wedge means extending between the plate and the lever and also through the slot, said wedge means being adapted to engage the roller to retract it against the action of said spring means whereby the lever may be moved along the quadrant.

3. A lever construction comprising a pivotally mounted lever, a quadrant concentric about the axis of the lever, said lever having an opening adapted to receive the quad-

rant, the side of the opening closest the axis of the lever being curved to fit snugly adjacent the quadrant and the opposed side of the opening being inclined relative to the outer face of the quadrant, a roller located 70 between said inclined side of the opening and the outer face of the quadrant, a plate closing the larger end of said opening in the lever, a spring interposed between said plate and the roller, another plate fixed to the 75 lever to close the smaller end of said opening, said lever being cut away to form two radial slots adjacent the last mentioned plate, a push rod having two spaced legs adapted to be slidably received in said slots, 80 said legs having tapered ends adapted to engage against the roller to push it against the tension of the spring upon downward movement of the push rod.

In testimony whereof I affix my signature. 85
